UNITED STATES PATENT OFFICE.

ALBERT L. ROHRBACHER, JR., OF BOSTON, MASSACHUSETTS.

WORK SHOE.

Application filed November 20, 1926. Serial No. 149,612.

This invention relates to shoes, and particularly to shoes for the use of foundrymen, workmen or others who are subjected to the risk of having molten metal, chemicals or other materials splash into or enter the shoe. 5

Not only is it important to make provision permitting the stripping of the shoe open instantly, in case of accident, but it is also 10 important to prevent, as far as possible, the entrance of such materials through the vent between the two lapped edges or flaps of the shoe-upper.

The present invention satisfies both these 15 important needs by providing a construction of shoe that positively prevents the upper from opening accidentally under the stresses of the foot inside, while yet permitting the stripping open of the vent by 20 a single rapid sweep of the hand, and that also positively prevents ingress of such substances through the vent opening as the shoe is normally worn.

In general the invention comprises a shoe 25 whose vent is held closed by quick releasable fasteners, the vent itself being sealed by a foldable or collapsible tongue or sealing portion extending from the flap on one side of the vent to the flap on the other 30 side of the vent so as to form an extensible guard-strip connecting the two flaps or sides of the shoe-upper.

These and other features of the invention will be described in the following specification 35 and will be defined in the claims hereto annexed.

In the accompanying drawings I have illustrated the embodiment of the principles of this invention in concrete forms in which:

40 Figure 1 is an outside elevation of a shoe containing my said improvements.

Figure 2 is an edge view of the upper at about the sectional line 2—2 on Figure 1, showing one construction for sealing the 45 vent.

Figure 3 is a similar view showing a somewhat modified form of means for sealing the vent.

The shoe itself, as actually made, 50 comprises the shoe-bottom 1, the vamp 2, the counter 3 and upper 4, but by preference the vent or slit extending from the top of the upper to its juncture with the vamp is located well beyond the middle front line, 55 preferably on the outside of the shoe, the

inner flap forming the edge portion of the upper on one side of the vent, as shown at 4^a, being carried well beyond the edge portion of the outer flap 4^b so as to produce a substantial overlap between these two parts of 60 the upper.

In the outside flap is secured a series of spring-jaw socket members 5, the free ends of whose spring-jaws 5^a point downwardly in approximate parallelism with the edge 65 of the flap 4^b, so that a quick outward pull exerted at the top edge of the flap 4^b serves to release almost instantaneously, by a single sweep of the hand, the entire series of fasteners. These fasteners are of a well known 70 type and their spring-jaws 5^a are arranged so as to resist release except by a pull from above outwardly. As will be seen from the drawings, they are aligned in a longitudinal row so that each is released by an outward 75 pull against its upper portion.

These socket members are placed to register with co-acting grooved or shouldered studs 6, attached to the opposite side of the vent, preferably by means of a separate flap 80 or stud-carrying strip 6^a, which is stitched or otherwise secured to the adjacent flap of the upper in order that the inside anchoring portion of the metal stud may not press directly against the foot but against the interposed leather flap, thereby preventing discomfort and the production of sores on the 85 foot of the wearer.

To seal or close the vent against the ingress of molten iron, chemicals or other substances that might splash from the floor or into which the foot might be thrust, I provide an extension or guard member 7, which, as shown in Figure 2, is secured to the flap 4^a by stitching or otherwise, and which is 90 carried across to the opposite side of the front of the foot and folded back with its inside face turned outward to lie against the inside surface of the outer flap 4^b, to which it is stitched or otherwise secured. 95 This tongue or guard, therefore, forms a folded sealing member which guards the foot against the entrance of any substance through the spaces between the fasteners, when the shoe is normally secured on the 100 foot.

It is quite possible to secure the same result by cutting the outside portion of the upper with such an excess of stock as to form this tongue or guard portion inte- 110

gral with the outside portion of the upper, as shown in Figure 3 at 7^a.

In this case the socket member of the fastener is secured to the flap 4^b of the upper precisely as before, the only difference being that instead of providing a separate extension piece 7, as in Figure 2, stitched to the forward edge of the outside portion of the upper 4, these two pieces are made in 10 one integral piece.

The stud-carrying strip 6^a and the stud 6 are constructed and arranged precisely as before, as in Figure 2, and the strip 6^a is attached to the outside member of the upper shoe-top by stitching, as previously described.

So long as the shoe-upper is kept intact there is no possibility of liquid or semi-liquid substances flowing into the interior of the 20 shoe through the vent. The doubled or folded protective portion of the upper, which may be termed a "tongue", completely excludes such material besides affording an extra thickness of leather or flexible material over the instep forming an additional protection for this exposed part of the foot. Nevertheless, the presence of this vent-sealing means in no wise interferes with the 25 instantaneous release of the shoe-upper fasteners to permit the stripping of the shoe from the foot.

It will, therefore, be seen that the shoe-upper or top comprises two sides or side members united at the back and of unequal 35 length from back to front so that their edge portions may overlap at some distance to one side of the medial longitudinal plane of the shoe, preferably on the outer side of the shoe to form a vent opening extending from 40 the upper edge downwardly to permit putting on and taking off the shoe, while the vent is closed by a flexible tongue forming a continuation or extension of the shorter or underneath flap sufficient to extend across 45 the line of the instep, folded back upon itself and be secured to the inside face of the outer flap.

For the purpose of securing quick stripping or release, while at the same time preventing the opening of the vent under the 50 severe internal stresses of the foot to which such shoes are subjected, or when the outer

flap catches against a molder's flask or other external object, it is important that the points or ends of the spring locking-jaws of each fastener extend downward in substantial alignment with one another, thereby locking each against release except by the outward pull at the top of the flap, which involves but a single movement of the hand by reason of such alignment. By the use of the sealing tongue or extension, in the manner described, the only possible place for the entrance of foreign matter is at the top edge of the shoe-upper which should be fitted as tightly as practicable, but which can be opened instantly for the removal of the shoe in case of such accident.

What I claim is:

1. A safety shoe embracing in its construction an upper cut to form mutually overlapped flaps to close a vent opening therein extending downward from the top edge of the upper on the outer side of the shoe, a stud-carrying strip secured to the outside face of the underneath flap with said flap interposed between the studs and an inserted foot, a plurality of coacting quickly releasable fastener members secured to the exterior flap of the upper in position to releasably engage the studs carried by said strip, and a vent-sealing tongue whose inner edge portion is secured to the outside face of the underneath flap and whose outer edge portion is secured to the inside face of the exterior flap. 70

2. A safety shoe embracing in its construction a shoe upper top, to one of whose sides is secured a series of externally projecting fastening studs, both sides of said upper being provided with forward extensions secured together to form a flexible vent-closing flap foldable over the instep to overlapped relation with said studs, and a series of inwardly opening socket members 90 secured to said vent-closing flap in position to interlockingly engage the respective studs to hold the flap against opening under lateral strains, while allowing the flap to be stripped from the studs by an outward pull 100 applied at its top.

In witness whereof, I have subscribed the above specification.

ALBERT L. ROHRBACHER, JR.
